UNITED STATES PATENT OFFICE.

EDWARD F. CHAFFEE, OF SYRACUSE, NEW YORK, ASSIGNOR TO THE O. M. EDWARDS CO. INC., OF SYRACUSE, NEW YORK, A CORPORATION OF NEW YORK.

WINDOW-SASH HOLDER.

Application filed November 4, 1925. Serial No. 66,702.

This invention relates to window construction and particularly to means for releasing the sash from snug engagement with the frame and the sill preliminary to lifting the sash.

The invention consists in the novel features and in the combinations and constructions hereinafter set forth and claimed.

In describing this invention reference is 10 had to the accompanying drawing in which like characters designate corresponding parts in all the views.

Figure 1 is a fragmentary front elevation of a window construction embodying this 15 invention.

Figure 2 is a transverse sectional view taken on line 2—2 Figure 1.

Figure 3 is an inner face view of the detached sash fastener.

20 Figure 4 is an edge view of the detached sash fastener.

This window construction comprises generally a window frame formed with a window guide including an outer stop, a sash 25 movable along the frame, a combined sash fastener and window releasing means arranged to normally force the sash toward the stop, and when operated preliminarily to lifting the sash to force the sash away 30 from the stop and away from the sill of the frame, and also edgewise away from the guides. The invention further includes the construction of a combined sash fastener and holder whereby the sash is moved edgewise and vertically and also at a right angle 35 to its plane when the sash fastener is operated to lift the sash off the sill.

1 designates the window frame having outer stop 2, which forms part of the guide 40 3 for the sash. The sash fastening and releasing means comprises units located preferably at the inner lower corners of the sash, each unit being of the general construction shown in my Patent 1,349,046, October 10, 1920, and in my application 45 667,496, filed October 9, 1923, with a sash releasing attachment added.

Each of the units comprises a base or housing which incloses a recess 5 opening through the inner face of the housing. The base 4 is mounted on the sash in such position as to close the open rear side of the recess. In addition the sash fastener here

illustrated comprises a bolt 6 slidably mounted in the housing 4 and operated by 55 a lever 7, pivoted at 8 in the housing and having an angular arm 9 connected to the bolt to actuate it, and having a longer arm extending to the outside of the housing and being normally arranged in juxtaposition to 60 a stationary pinch handle 10, provided on the housing.

The bolt 6 is beveled at 11 and it is engaged or coacts with a rack 12 having a complementary beveled face 13, the beveled faces 11 and 13 being so arranged that the bolt 6, when thrust outwardly by its spring 14, forces the sash against the stop 2. The construction of the sash holder thus described is old in so far as this invention is 70 concerned.

Each of the units of the sash holding means is provided with sash releasing means which is operated when the bolt 6 is withdrawn, and as here shown this sash releasing means is actuated directly by the lever 7. 75

As here shown the releasing means is a pusher 15 movable through a suitable passage in the lower edge of the housing 4, with its inner end arranged in the path of 80 the lever 7 and normally spaced therefrom, and with its outer lower end arranged to push against the sill when the lever 7 is moved toward the pinch handle 10. This pusher 15 as here shown is inclined out of 85 the vertical, that is out of a vertical plane parallel to the general plane of the sash in order to force the sash away from the stop 2 and also inclined away from the side edge of the sash in order to force the sash edge- 90 wise away from the guide 13, and while the pushers are moving endwise they lift the sash away from the sill thus breaking the sash away from all surfaces to which it tends to adhere. 95

Usually the operator naturally does not operate the handle levers 7 of the units simultaneously, but operates one lever slightly in advance of the other. Therefore, the pushers do not ordinarily act against 100 each other in forcing the sash edgewise but the sash is moved edgewise in one direction and then in the other direction. Owing to the arrangement of the pusher where it is acted upon directly by the lever 7 in contradic- 105 tion to being actuated by a cam action

or from the bolt 6, a powerful action or leverage is obtained without any appreciable effort on the part of the operator.

What I claim is:—

- 5 1. In a window construction the combination of a window frame formed with a guide and an outer stop, a sash movable along the guide and the stop, a sash fastener on the inner side of the sash including a holding member, a rack extending along the guide and coacting with the said member, the holding member and the rack being constructed to force the sash toward the outer stop, the sash fastener further comprising 10 means for operating the holding member and a sash release arranged to press against the sill of the window frame and to be operated by the operating means of the holding member and comprising of a pusher inclined upwardly out of the vertical in such direction 15 as to force the sash away from the outer stop.
2. In a window construction the combination of a window frame formed with a guide and an outer stop, a sash movable along the guide and the stop, a sash fastener on the inner side of the sash including a holding member, a rack extending along the guide and coacting with the said member, the holding member, the rack being constructed to force the sash toward the outer stop, the sash fastener further comprising means for operating the holding member and a sash release arranged to press against the sill of the window frame and to be operated by the operating means of the holding member and comprising a pusher inclined upwardly out of the vertical in such a direction as to force the sash away from the guide. 20
3. In a window construction the combination of a window frame formed with a guide and an outer stop, a sash movable along the guide and the stop, a sash fastener on the inner side of the sash including a holding member, a rack extending along the guide and coacting with the said member, the holding member and the rack being constructed to force the sash toward the outer stop, the sash fastener further comprising 25
4. In a window construction the combination of a window frame formed with a guide and an outer stop, a sash movable along the guide and the stop, a sash fastener on the inner side of the sash including a holding member, a rack extending along the guide and coacting with the said member, the holding member, the rack being constructed to force the sash toward the outer stop, the sash fastener further comprising means for operating the holding member and a sash release arranged to press against the sill of the window frame and to be operated by the operating means of the holding member and comprising a pusher inclined upwardly out of the vertical in such a direction as to force the sash away from the guide. 30
5. In a window construction the combination of a window frame formed with a guide and an outer stop, a sash movable along the guide and the stop, a sash fastener on the inner side of the sash including a holding member, a rack extending along the guide and coacting with the said member, the holding member, the rack being constructed to force the sash toward the outer stop, the sash fastener further comprising means for operating the holding member and a sash release arranged to press against the sill of the window frame and to be operated by the operating means of the holding member and comprising a pusher inclined upwardly out of the vertical in such a direction as to force the sash away from the outer stop. 35
6. In a window construction the combination of a window frame formed with a guide and an outer stop, a sash movable along the guide and the stop, a sash fastener on the inner side of the sash including a holding member, a rack extending along the guide and coacting with the said member, the holding member, the rack being constructed to force the sash toward the outer stop, the sash fastener further comprising means for operating the holding member and a sash release arranged to press against the sill of the window frame and to be operated by the operating means of the holding member and comprising a pusher inclined upwardly out of the vertical in such a direction as to force the sash away from the outer stop. 40
7. In a window construction comprising a frame formed with a guide and an outer stop, a sash movable along the guide, a rack extending along the guide and the stop, a sash holding mechanism including means coacting with the rack to hold the sash from movement and force the sash toward the outer stop and means for forcing the sash away from the outer stop when the sash holding means is released, said means also coacting with the sill to start the sash away from the sill. 45
8. In a window construction comprising a frame formed with a guide and an outer stop, a sash movable along the guide, a rack extending along the guide and the stop, a sash holding mechanism including means coacting with the rack to hold the sash from movement and force the sash toward the outer stop and means for forcing the sash away from the outer stop when the sash holding means is released, said means also coacting with the sill to start the sash away from the sill and comprising a pusher coacting with the sill and inclined upwardly out of the vertical away from the stop and the adjacent edge of the sash. 50

means for operating the holding member and a sash release arranged to press against the sill of the window frame and to be operated by the operating means of the holding member and comprising a pusher inclined upwardly out of the vertical away from the edge and the plane of the sash. 55

4. A window construction comprising a frame formed with a guide and an outer stop, a sash movable along the guide, a rack extending along the guide and the stop, a sash holding mechanism including means coacting with the rack to hold the sash from movement and force the sash toward the outer stop and means for forcing the sash away from the outer stop when the sash holding means is released. 60

5. A window construction comprising a frame formed with a guide and an outer stop, a sash movable along the guide, a rack extending along the guide and the stop, a sash holding mechanism including means coacting with the rack to hold the sash from movement and force the sash toward the outer stop and means for forcing the sash away from the outer stop when the sash holding means is released, said means also coacting with the sill to start the sash away from the sill. 70

6. A window construction comprising a frame formed with a guide and an outer stop, a sash movable along the guide, a rack extending along the guide and the stop, a sash holding mechanism including means coacting with the rack to hold the sash from movement and force the sash toward the outer stop and means for forcing the sash away from the outer stop when the sash holding means is released, said means also coacting with the sill to start the sash away from the sill and comprising a pusher coacting with the sill and inclined upwardly out of the vertical away from the stop and the adjacent edge of the sash. 75

In testimony whereof, I have hereunto signed my name, at Syracuse in the county of Onondaga, and in the State of New York, this 26th day of Oct., 1924.

EDWARD F. CHAFFEE.
